UNITED STATES PATENT OFFICE

170,650

COMBINED MATCH DISPENSER AND CONDIMENT HOLDER

Francis R. McNine, Bridgeport, Conn.

Application February 19, 1953, Serial No. 23,691

Term of patent 14 years

(Cl. D44—6)

To all whom it may concern:

Be it known that I, Francis R. McNine, a citizen of the United States, residing at Bridgeport, county of Fairfield, State of Connecticut, have invented a new, original, and ornamental Design for a Combined Match Dispenser and Condiment Holder, of which the following is a specification, reference being had to the accompanying drawing, forming a part hereof.

Fig. 1 is a perspective view of a combined match dispenser and condiment holder, showing my new design;

Fig. 2 is a top plan view thereof, and
Fig. 3 is a front elevation.

I claim:

The ornamental design for a combined match dispenser and condiment holder, substantially as shown.

FRANCIS R. MCNINE.
